UNITED STATES PATENT OFFICE.

OTTO E. BORNHAUSER AND JOHN EDWARD HERMAN, OF SANDUSKY, OHIO.

MOLD FOR MAKING BUILDING BLOCKS.

Application filed February 17, 1923. Serial No. 619,605.

To all whom it may concern:

Be it known that we, OTTO E. BORNHAUSER and JOHN EDWARD HERMAN, citizens of the United States, residing at Sandusky, in 5 the county of Erie and State of Ohio, have invented a new and useful Mold for Making Building Blocks, of which the following is a specification.

Our invention relates to improvements 10 in molds for making building blocks, and more especially to a mold suitable for making a hollow product composed of cementitious material consisting largely of gypsum.

Our improved mold is preferably oblong 15 in plan and preferably comprises the following:—A substantially horizontal mold-bottom, two longitudinal plates disposed to form substantially parallel opposite side 20 walls respectively of the material-receiving chamber of the mold and normally held in a substantially vertical position and adapted to be loosened in relation to the product to be formed in said chamber, a transverse 25 plate disposed to form one end wall of said chamber and normally held in a substantially vertical position and adapted to be moved into a position permitting movement of said product at said transverse plate sub- 30 stantially horizontally endwise of and from between the longitudinal plates, a slid- 35 able transverse plate arranged to form the other end wall of said chamber and normally in position to be slid between the longitudinal plates toward the first-mentioned transverse 40 plate and having vertically spaced holes which extend from side to side of said 45 slid- able plate, a stationary abutment-member arranged to form an abutment for the outer side of said slid- able plate, and vertically 50 spaced cores which are substantially parallel with the path of and unattached to said slid- able plate and rigid with said abutment-member and engage the different aforesaid holes respectively and, in the normal 55 position of said slid- able plate, are closely embraced by said plate at the inner side of the plate and extend through said plate and from said plate in the direction of and taper toward the first-mentioned transverse plate.

One object of this invention is to have the walls of said holes and the core-portions which extend through said holes in the normal position of the hereinbefore mentioned slid- able plate relatively arranged and con-

toured to effect the formation, around and endwise of each of said core-portions in said normal position of said plate, of a space increasing in size transversely toward the 60 outer side of said plate.

Another object is to have said slid- able plate and the hereinbefore mentioned abut- 65 ment-member relatively contoured to effect contact between said abutment-member and said plate only centrally between the side edges of said plate in the normal position of the plate.

Another object is to construct a mold of the character indicated from which the 70 building block or product formed in the mold can be readily removed horizontally from the mold, and to utilize the herein- 75 before mentioned slid- able plate, independ- ently of the other plates employed in form- ing upright walls of the mold, in effecting a forcible removal of said product hori- zontally from the mold.

Another object is to utilize movement of 80 said slid- able plate endwise of the mold in one direction to remove a hollow product from a mold comprising the hereinbefore mentioned cores, and to utilize movement of said plate in the opposite direction in cleaning said cores.

Another object is to facilitate the work of the hereinbefore mentioned slid- able plate in discharging the product from the mold.

Another object is to render our improved mold simple and durable in construction and 90 reliable and convenient in its operation, and more especially to facilitate and insure the maintenance of the mold in a clean condition.

With these objects in view, and to attain 95 any other object hereinafter appearing, our invention consists in certain features of construction, and combinations and relative ar- rangements of parts, hereinafter described in this specification, pointed out in the 100 claims, and illustrated in the accompanying drawings.

In said drawings, Figure 1 is a top plan of a mold embodying our invention. Fig. 2 is a vertical longitudinal section taken along the line 2—2 in Fig. 1. Figs. 3 and 4 are vertical transverse sections taken along the line 3—3 and line 4—4 respectively in Fig. 2. Fig. 5 is a vertical section, in detail, showing a portion of a core of the 110 mold and the adjacent portion of the slid- able transverse plate surrounding said

core. Fig. 6 is a vertical section taken along the line 6—6 in Fig. 5. Fig. 7 is a side view of the mold, with the pivoted plates of the mold swung outwardly and downwardly. 5 Fig. 8 is a side view corresponding with Fig. 7, except that in Fig. 8 the hereinbefore mentioned slideable plate is shown as having been slid endwise of the mold as required to discharge the product from the mold. 10 Fig. 9 is a transverse vertical section taken along the line 9—9 in Fig. 8. Figs. 5 and 6 are drawn on a larger scale than Figs. 1, 2, 3, 4, 7, 8 and 9, and portions are broken away in the drawings to reduce their size. 15 Referring to said drawings, 12 indicates a bench or table on which is mounted the substantially horizontal stationary metal bottom 13 of our improved mold which is preferably oblong in plan, and said bottom 20 preferably consists of a metal plate lying on said table and removably secured to the table by bolts or screws 14, as shown in Fig. 2, and 15 (see Figs. 1, 2, 3 and 4) indicates the material-receiving interior chamber of 25 the mold, and in said chamber a building tile or block is adapted to be formed. Said chamber is rectangular in plan and open at its upper end to permit the feeding of wet or moist cementitious material into said 30 chamber from above in any approved manner.

Our improved mold (see Figs. 1, 2, 3 and 4) is shown as comprising a pair of spaced upright metal side plates 16 which extend 35 longitudinally of the mold and are disposed to form two substantially parallel opposite side walls respectively of the chamber 15, and said mold also comprises a pair of transverse upright metal plates 17 and 18 40 which are disposed to form opposite end walls respectively of said chamber. The mold-bottom 13 extends under the plates 16, 17 and 18.

The transverse plate 17 (see Figs. 1, 2 45 and 3) extends between the longitudinal plates 16 and has narrow side edges overlapped by said longitudinal plates and is substantially vertical and rests on the mold-bottom 13, and said transverse plate is nor- 50 mally adapted and in position to be slid bodily between and independently of the plates or walls 16, in the direction and independently of the transverse plate 18 and normally held against movement in the op- 55 posite direction by a substantially vertical stationary abutment-member 20 at the outer side of the slideable plate 17, and said mem- ber 20 is arranged to form an abutment for said outer side of said slideable plate in the 60 normal position of the plate.

The mold-bottom 13 terminates, at its end which is adjacent the transverse plate 18, in an undercut transverse edge 21 shown in Fig. 2, and said plate 18 (see Figs. 1, 2 and 65 4) is normally held in a substantially ver-

tical position and adapted to be moved into a position permitting movement of a building block substantially horizontally at said plate endwise of and from between the longitudinal plates 16, as will hereinafter more 70 fully appear.

The transverse plate 18 (see Figs. 1 and 2) is provided, at its lower end, with a downwardly and outwardly projecting ear 22 which is pivoted, as at 23, horizontally and 75 transversely of the mold, to an ear or member 24 formed on and projecting from the mold-bottom 13 below the top surface of said bottom. Said plate 18 is therefore pivoted, at its lower end and externally of 80 the chamber 15, to the mold-bottom 13 and arranged as required to permit the plate to swing outwardly and downwardly when the plate is free to be swung outwardly and downwardly. Said plate 18 has an outwardly facing beveled bottom edge 25, as shown in Fig. 2, and in its normal and substantially vertical position only rests at the lower extremity of said edge on the top 85 surface of the mold-bottom 13 near the undercut edge 21 of said bottom, and said undercut edge 21, and the contact of said plate 18 only at said extremity of its bottom edge with the mold-bottom, facilitate the keeping 90 of adjacent portions of the mold-bottom and said plate in a clean condition. We would 95 here remark that the plate 18 extends between the longitudinal plates 16 which, in the normal and substantially vertical position of said plate 18, abut against the side edges of said plate 18, as shown in Fig. 1. Said plate 18 has its outer side beveled, as at 26 in Fig. 1, at the side edges of the plate to lessen the contact between said plate 18 and each longitudinal plate 16 and to facilitate the keeping of the joint between said 100 plates in a clean condition.

The transverse plate 18 is normally held in a substantially vertical position (see Fig. 2), and means for preventing movement of 105 said plate outwardly in said position of the plate comprises an upright brace 27 ar- 110 ranged at the outer side of the plate cen- trally between the side edges of the plate. Said brace is pivoted at its upper end, as at 28, horizontally and transversely of the mold, to an ear 29 formed on the plate 18. Said brace at its lower end engages the top 115 of the table 12 and is disposed as required for holding the connected plate 18 in its 120 substantially vertical and normal position. Obviously the actuation of the said brace outwardly in any approved manner renders the plate 18 free to be swung outwardly and 125 downwardly from its substantially vertical and normal position shown in Figs. 1 and 2 into a horizontal position shown in Figs. 7 and 8 and onto pins or upwardly projecting members 30 with which the table 12 is pro- 130 vided. The relative arrangement of the

parts is such that the plate 18, upon being swung into said horizontal position, is below the mold-chamber 15 and therefore in a position permitting movement thereover of 5 a building block or product substantially horizontally from between the longitudinal plates 16.

The mold-bottom 13 (see Figs. 1 and 3) is provided, adjacent the lower end of each 10 side edge of each longitudinal plate 16, with a horizontally outwardly projecting member 31, and said plate is provided adjacent said member 31 with a member 32 which projects from the outer side of said plate at a point 15 above said bottom laterally and outwardly and terminates at its outer end in an ear 33 arranged at one side of said member 31, and a pivotal pin 35, arranged horizontally and longitudinally of said plate and substantial- 20 ly at a right angle to the axis of the pivoted transverse plate 18, is shown extending from within said ear 33 into the intermediate hole of a horizontal row of three correspondingly arranged holes 36 which are formed in and 25 spaced endwise of said member 31. Obviously the longitudinal plates 16, upon disengaging the pins 35 from the intermediate holes in the members 31 of the mold-bottom, can be readjusted laterally to bring the pins 30 35 into engagement with the inner holes or outer holes of the rows of holes 36 in said members 31. Obviously the mold-chamber 15 is reduced or increased in width accord- 35 ing as the plates 16 are readjusted toward or from each other, and of course the illus- 40 trated transverse plates 17 and 18 are re- placed by narrower or wider plates accord- 45 ing as the longitudinal plates 16 are read- justed to reduce or increase the distance be- tween them. By the hereinbefore described construction it will be observed that each longitudinal plate 16 is pivoted, at its lower end and externally of the chamber 15, to the mold-bottom 13 and arranged as required to 45 permit the plate to swing outwardly and downwardly when the plate is free to be swung outwardly and downwardly.

Each longitudinal plate 16 has an outwardly facing beveled bottom edge 37, as 50 shown in Fig. 4, and, in its normal and substantially vertical position, only rests at the lower extremity of said edge on the top surface of the mold-bottom 13, and said mold-bottom is wide enough to extend under the 55 longitudinal plates 16 in the different hereinbefore mentioned lateral readjustments of said plates. Contact of the longitudinal plates 16 only at the lower extremities of their bottom edges 37 with the mold-bottom 60 13 facilitates maintenance of the joints between the mold-bottom and said plates in a clean condition.

Each longitudinal plate 16, in its normal and substantially vertical position (see Fig. 65 4), is braced at its outer side, centrally be-

tween the side edges of the plate, by an upright brace 38 pivoted at its upper end, as at 39, horizontally and longitudinally of the mold to an ear 40 with which said plate is provided, and said brace 38 at its lower end 70 engages the top of the table 12 and is disposed as required for holding the connected plate 16 in its substantially vertical and normal position. Obviously the actuation of the said brace 38 outwardly in any ap- 75 proved manner renders the connected plate 16 loose in relation to a building block or product formed in the mold and facilitates the removal of said product endwise of and from between the longitudinal plates 16. 80 Preferably the longitudinal plates 16, upon rendering the connected braces 38 inoperative by actuating said braces outwardly, are swung outwardly and downwardly from their substantially vertical and normal posi- 85 tion shown in Figs. 1 and 4 into a depending position shown in Figs. 7, 8 and 9, and the top of the table 12 is slotted or cut away, as at 41, to permit such movement of said plates. 90

The abutment-member 20 (see Fig. 1) has two substantially vertical sides 42 facing and converging toward the outer side of the 95 slidable plate 17 and substantially meeting at their adjacent extremities. Said outer side of said slidable plate comprises two surfaces 43 which face and converge toward the abutment-member 20 and substantially meet at their adjacent extremities, and the relative arrangement of the parts is such that 100 the substantially meeting extremities of said surfaces 43 are directly opposite the afore- said substantially meeting extremities of the sides 42 of said abutment-member. It will be observed, therefore, that the slidable plate 105 17 and the abutment-member 20 are relative- 110 ly contoured to effect contact between them only centrally between the side edges of said plate in the normal position of the plate so as to facilitate the maintenance of the op- 115 posing surfaces of said members 17 and 20 in a clean condition.

The mold-bottom 13 (see Fig. 2) extends under the abutment-member 20 and a suitable distance outwardly beyond said abut- 115 ment-member, and a substantially vertical standard 45, arranged at the outer side of said abutment-member, is preferably formed integral with said bottom, and said abut- 120 ment-member is removably secured to said standard by bolts or screws 46.

The slidable transverse plate 17 (see Figs. 2 and 3) is shown as having three vertically spaced horizontal holes 47 which are formed between the top and bottom edges of said 125 plate and centrally between the side edges of the plate and extend through said plate from the inner side of the plate to the outer surfaces 43 of the plate. Preferably each hole 47 (see also Fig. 5) is uniform in dia- 130

ter from end to end and substantially parallel with the path of the slidable plate 17.

Our improved mold (see Figs. 2, 3 and 4) is shown as comprising three vertically spaced substantially horizontal stationary hollow cores 48 which extend endwise of the mold and engage the different holes 47 respectively in the slidable plate 17 and are substantially parallel with the path of said plate. Preferably said cores are formed integral with the abutment-member 20 and extend therefore from said abutment-member into the holes 47 and are unattached to the slidable plate 17 and, in the normal position of said plate, extend through said plate and from the inner side of said plate in the direction of and taper toward the pivoted transverse plate 18, and the relative arrangement of the parts is preferably such that in its substantially vertical and normal position said pivoted plate 18 abuts against the adjacent ends of said cores. The taper of the cores 48 toward the pivoted transverse plate 18 is exaggeratedly illustrated. Each core 48 (see Figs. 2, 3, 5 and 6) is closely embraced by the slidable plate 17 at the inner side of said plate in the normal position of the plate and has its portion which extends through said plate in said position of the plate tapering or gradually reduced transversely toward the outer side of the plate and therefore toward the abutment-member 20. Obviously, therefore, the walls of the holes 47 and the core-portions which extend through said holes in the normal position of the slidable plate 17 are relatively arranged and contoured to effect the formation, around and endwise of each of said core-portions in said position of said plate, of a space increasing in dimensions transversely toward and extending to the outer side of said plate and communicating with the space between opposing surfaces 42 and 43 of the members 17 and 20. We would here remark that the attachment of the abutment-member 20 removably to the standard 45 permits the replacement of said abutment-member, when required, by an abutment-member having cores larger or smaller in dimensions than the illustrated cores 48.

Means for actuating the slidable plate 17 (see Fig. 2) are provided and preferably comprise two vertically spaced substantially horizontal rods 50 which are substantially parallel with the path of said plate and threaded into the central portion of said plate and extend from said plate loosely through holes 51 in the abutment-member 20 and loosely through holes 52 in the standard 45 and outwardly beyond said standard a suitable distance. Said rods 50 are connected together at their outer ends by a handle 53 to which is attached one end of a cable 54 attached at its other end to and

operatively engaging a windlass 55 formed by one end portion of a horizontal shaft 56 which, as shown in Figs. 1 and 2, is arranged at the outer side of the standard 45 and between and substantially at a right angle to said rods and supported from brackets 57 rigid with said standard. Said shaft (see Fig. 3) is provided with a crank 58 for rotating the shaft.

In operation, the mold-chamber 15 is filled with wet or moist cementitious material in any approved manner, and when said material has sufficiently set or hardened in said chamber to form the desired building block or product the braces 27 and 38 are swung outwardly to loosen the pivoted plates 16 and 18 in relation to said product so as to permit the longitudinal plates 16 to release the product and so as to permit the pivoted transverse plate 18 to be swung outwardly and downwardly into a horizontal position shown in Fig. 7, whereupon the windlass 55 is rotated in the direction required to wind up cable so as to actuate the rods 50 and connected slidable plate 17 in the direction of the lowered pivoted transverse plate 18 and thereby shove the product over said lowered plate 18. Fig. 7 shows a building block 60 which has been formed in the mold and which is to be removed endwise of and from between the longitudinal plates 16, and Fig. 8 shows said block as having been removed from between said plates and onto the lowered pivoted transverse plate 18 from which said block is received by a conveyer (not shown) or removed in any other approved manner. Because of the cores 48 obviously the illustrated product is a hollow building block having parallel holes 61 shown in broken lines in Fig. 8, and the tapering of said cores in the direction of the pivoted transverse plate 18 obviously facilitates loosening of the product in relation to said cores during movement of the product endwise of the mold and from the mold-bottom 13 to and over said lowered plate 18. Obviously upon the removal of said building block from said lowered plate 18 the handle 53, and consequently the rods 50 and connected slidable plate 17, are pulled in the direction and to the extent required to return said slidable plate into its normal position in which, as hereinbefore indicated, said slidable plate is in contact with the abutment-member 20, and upon said return of said slidable plate into its normal position the plates 16 and 18 are returned into and held in their substantially vertical and normal position preparatory to and during the next production of a building block or product in the mold. We would here remark that by the hereinbefore described construction and relative arrangement of parts the slidable plate 17, during movement of said plate from the posi-

tion shown in Figs. 7 and 8 into its normal position shown in Figs. 1 and 2, serves to insure clean joints between said plate and the cores 48 at the inner side of the plate 5 upon said movement of said plate, and the hereinbefore described taper of the core- portions which are surrounded by said plate in the normal position of said plate, and the enlargement, toward said abutment- 10 member, of the space formed around and endwise of each core between said core and the core-surrounding portion of said plate in said normal position of said plate, permit and facilitate the escape of material 15 from between said portion of said plate and said core into the space formed, as hereinbefore described, between each of the converging sides or surfaces 42 of said abutment-member and the opposing surface of 20 the converging surfaces 43 of said plate.

What we claim is—

1. A mold of the character indicated comprising a pair of spaced opposite upright walls and two spaced opposite upright walls 25 arranged substantially at a right angle to the first-mentioned walls, one of the second-mentioned walls being a slidable wall disposed to move between and independently of the first-mentioned walls, the other of said 30 second-mentioned walls being movable into a position permitting movement of a building block or product substantially horizontally from between the first-mentioned walls by said slidable wall, and said slidable wall 35 being normally in position to be slid substantially horizontally and independently of said first-mentioned walls in the direction in which the inner side of said slidable wall faces.
- 40 2. A mold of the character indicated having a bottom and comprising a pair of spaced plates which are disposed to form opposite upright walls respectively of the mold and adapted to be rendered loose in relation to a building block or product 45 formed between said walls, said mold also comprising a pair of spaced opposite plates disposed to form upright walls of the mold, one of the second-mentioned plates being a 50 slidable plate arranged substantially at a right angle to and extending between the first-mentioned plates and normally in position to be slid independently of said first-mentioned plates in the direction and independently of the other plate of the second- 55 mentioned pair of plates and normally immovable in the opposite direction, the last-mentioned plate of said second-mentioned pair of plates being movable into a position 60 permitting movement of the aforesaid product from between the first-mentioned plates by the aforesaid slidable plate, and said first-mentioned plates having outwardly fac- 65 ing beveled bottom edges and normally resting, at the lower extremities of said edges,

on the top surface of the aforesaid bottom.

3. A mold of the character indicated comprising two spaced opposite upright side plates, and two spaced upright opposite transverse plates extending from one to the 70 other of the side plates, one transverse plate being a slidable plate extending between the side plates and normally in position to be slid independently of the side plates in the direction and independently of the other 75 transverse plate and normally immovable in the opposite direction, and the last-mentioned transverse plate being movable into a position permitting movement of a building block or product from between and independently of the side plates by the aforesaid slidable plate.

4. A mold of the character indicated comprising a pair of spaced opposite upright walls and two spaced upright walls extending from one to the other of the first-mentioned walls, one of the second-mentioned walls being substantially horizontally pivoted at one end and externally of and below the chamber formed between said walls and arranged to be swung outwardly into a position lower than said chamber, and the other of the second-mentioned walls extending between the first-mentioned walls and being a slidable wall which is normally spaced the 90 maximum distance from the aforesaid pivoted wall and adapted to be slid independently of the first-mentioned walls the distance required to effect the removal of a building block or product substantially horizontally over said pivoted wall and from between the first mentioned walls by the aforesaid slidable wall upon swinging said pivoted wall into the aforesaid position.

5. A mold of the character indicated comprising a substantially horizontal bottom, two spaced opposite side walls, and two transverse plates disposed to form opposite end walls respectively of the mold, one transverse plate having an outwardly fac- 105 ing beveled bottom edge and being in contact at the lower extremity of said edge with the top surface of the aforesaid bottom and pivoted at its lower end to said bottom, said transverse plate extending from one to the 110 other of the aforesaid side walls and arranged to be swung outwardly into a position lower than said surface, the other transverse plate being a slidable plate normally in position to be slid between and independently of said side walls in the direction required to effect the removal of a building block or product substantially horizontally over the pivoted transverse plate upon swinging said pivoted plate into the aforesaid position, and the aforesaid bottom terminating adjacent the pivoted transverse plate in an undercut transverse edge.

6. A mold of the character indicated comprising a substantially horizontal bottom, 130

6

a pair of spaced opposite and laterally adjustable upright walls, and two spaced opposite upright walls arranged substantially at a right angle to said adjustable walls, 5 one of the second-mentioned walls being a slidable wall disposed to move between and independently of the first-mentioned walls, the other of said second-mentioned walls being movable into a position permitting 10 movement of a building block or product substantially horizontally from between the first-mentioned walls by said slidable wall, said slidable wall being normally in position to be slid substantially horizontally 15 and independently of said first-mentioned walls in the direction in which the inner side of said slidable wall faces, and the aforesaid bottom extending under said first-mentioned walls in different adjustments of said first-mentioned walls. 20

7. A mold of the character indicated comprising a pair of spaced plates which are disposed to form two opposite upright walls respectively of the mold, a pair of spaced 25 opposite plates which are arranged substantially at a right angle to the first-mentioned plates and disposed to form upright walls of the mold, one of the second-mentioned plates being a slidable plate which extends 30 between the first-mentioned plates and is normally in position to be slid substantially horizontally in the direction in which the inner side of said slidable plate faces, the other of the second-mentioned plates being 35 movable into a position permitting movement of a building block or product substantially horizontally from between the first-mentioned plates by said slidable plate, and an upright stationary abutment-member 40 at the outer side of and for said slidable plate, said abutment-member having two sides which are opposite and converged toward said slidable plate, and said slidable plate abutting, in its normal position, 45 against said abutment-member at adjacent portions of said sides of said abutment-member.

8. A mold of the character indicated comprising a pair of spaced opposite upright 50 walls, two spaced opposite upright walls extending from one to the other of the first-mentioned walls, one of the second-mentioned walls being a slidable wall which is normally in position to be slid substantially 55 horizontally in the direction in which the inner side of said slidable wall faces, the other of the second-mentioned walls being movable into a position permitting movement of a building block or product substantially 60 horizontally from between the first-mentioned walls by said slidable wall, and an upright stationary abutment-member at the outer side of and for said slidable wall, 65 comprising two surfaces which are arranged

opposite and converge toward said abutment-member.

9. A mold of the character indicated comprising a pair of spaced opposite upright walls, two spaced opposite walls extending from one to the other of the first-mentioned walls, one of the second-mentioned walls being a slidable wall which is normally in position to be slid substantially horizontally in the direction in which the inner side of 70 said slidable wall faces, the other of said second-mentioned walls being movable into a position permitting movement of a building block or product substantially horizontally from between the first-mentioned walls by said slidable wall, and an upright stationary abutment-member at the outer side of and for said slidable wall, said abutment-member having two surfaces converging toward and arranged opposite said slidable wall, and said slidable wall having two surfaces which converge toward and are opposite said abutment-member. 80

10. A mold of the character indicated comprising two spaced opposite upright 90 walls, two spaced upright walls extending from one to the other of the first-mentioned walls, one of the second-mentioned walls being a slidable wall which is arranged between and substantially at a right angle to 95 the first-mentioned walls and normally in position to move in the direction in which the inner side of said wall faces, the other of the second-mentioned walls being movable into a position permitting movement of 100 a building block or product from between the first-mentioned walls by said slidable wall, and a stationary core substantially parallel with the path of and unattached to and surrounded by and extending through 105 said slidable wall and in the normal position of said wall tapering from the inner side of said wall in the aforesaid direction, the core-surrounding portion of said slidable wall and the core-portion surrounded 110 by said wall having their opposing surfaces relatively arranged and contoured in the normal position of said wall to form a joint between said wall and said core-portion at the inner side of said wall and to space said 115 wall from and circumferentially of said core-portion substantially from said joint to the outer side of said wall.

11. A mold comprising a bottom, two spaced opposite upright walls, two spaced 120 upright walls extending from one to the other of the first-mentioned walls, one of the second-mentioned walls being a slidable wall which is arranged substantially at a right angle to and between the first-mentioned 125 walls and normally in position to move in the direction in which its inner side faces and normally immovable in the opposite direction, the other of the second-mentioned walls being movable into 130

1. a position permitting movement of a building block or product from between the first-mentioned walls by said slidable wall, and a stationary core which is substantially parallel with the path of and unattached to and extends through said slidable wall, said core being closely embraced at the inner side of and by said slidable wall in the normal position of said wall, said slidable wall having a hole formed therein for the extension therethrough of said core, said hole being substantially uniform in diameter from end to end, and said core having its portion which extends through said slidable wall in the normal position of said wall tapering toward the outer side of said wall.

12. A mold comprising a bottom, two spaced opposite side walls, a slidable end wall arranged substantially at a right angle to and between the first-mentioned walls and normally in position to move in the direction in which its inner side faces, an end wall arranged opposite and spaced from said slidable wall and movable into a position permitting movement of a building block or product in said direction from between the first-mentioned walls, a stationary abutment-member for the outer side of said slidable wall in the normal position of said wall, and a core rigid with said abutment-member and substantially parallel with the path of and unattached to and surrounded by said slidable wall and extending through said wall and from said wall in the aforesaid direction in said position of said wall, the core-surrounding portion of said slidable wall and the core-portion surrounded by said wall having their opposing surfaces relatively arranged and contoured in said position of said wall to form a joint between said wall and said core-portion at the inner side of said wall and to form a space interiorly of said wall and around said core-portion substantially from said joint to the space between the outer side of said wall and the aforesaid abutment-member.

13. A mold of the character indicated comprising two plates disposed to form opposite side walls of a material-receiving chamber, a transverse plate normally held in position to form one end wall of said chamber and adapted to be moved into a position permitting movement of the product formed in said chamber endwise of and from between the

first-mentioned plates, a slidable transverse plate extending between said first-mentioned plates and normally arranged to form the other end wall of said chamber and in position to be slid toward the first-mentioned transverse plate, a standard opposite and spaced from the outer side of said slidable plate and rigid with the aforesaid bottom, an upright abutment-member between the standard and slidable plate and secured to the standard and arranged to form an abutment for said plate in the normal position of the plate, spaced endwise movable rods secured to said slidable plate and extending substantially horizontally from the plate loosely through said abutment-member and standard, and means for actuating said rods in unison.

14. A mold comprising a bottom, two spaced opposite upright walls, a slidable upright wall for one end of the space between the first-mentioned walls and normally in position to move in the direction in which its inner side faces, an upright wall for the opposite end of said space and movable into a position permitting movement of a building block or product in said direction from between the first-mentioned walls, an abutment-member engaged by the outer side of said slidable wall in the normal position of said wall, and a stationary core substantially parallel with the path of and unattached to and surrounded by said slidable wall and extending through said wall and from said wall in the aforesaid direction in said position of said wall, said slidable wall and the abutment-member being relatively contoured to form a space between them in the normal position of said wall, said slidable wall closely embracing the core at the inner side of said wall and having a hole for receiving the core, and the core-portion which extends through said hole in the normal position of said wall being reduced in size transversely toward the last-mentioned space and out of contact with said wall in said position of said wall from said space substantially to the inner side of said wall.

In testimony whereof, we sign the foregoing specification, this 7th day of February, 1923.

OTTO E. BORNHAUSER.
JOHN EDWARD HERMAN.
